US0D1047637S

(12) **United States Design Patent** (10) **Patent No.:** **US D1,047,637 S**
(45) **Date of Patent:** **** Oct. 22, 2024**

(54) **SCISSORS**

(71) Applicant: **SHENZHEN BOSAIDONG TECHNOLOGY CO., LTD.**, Shenzhen (CN)
(72) Inventor: **Tianshi Cui**, Shenzhen (CN)
(73) Assignee: **SHENZHEN BOSAIDONG TECHNOLOGY CO., LTD.**, Shenzhen (CN)

(**) Term: **15 Years**

(21) Appl. No.: **29/869,398**

(22) Filed: **Dec. 30, 2022**

(30) **Foreign Application Priority Data**

Oct. 21, 2022 (CN) 202230698442.3

Primary Examiner — Eric L Goodman

Assistant Examiner — Adrian A Shwaiko

(57) **CLAIM**

The ornamental design for scissors as shown and described.

DESCRIPTION

FIG. 1 is a perspective view of scissors showing my new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a perspective view of the scissors where the scissors are in a configuration of use; and,

FIG. 11 is another perspective view of the scissors in a configuration of use.

The broken lines in the drawings depict portions of the scissors that form no part of the claimed design.

1 Claim, 11 Drawing Sheets
